ADVERTISING DISPLAY DEVICE FOR
DISPENSING CONTAINERS

Frank Cossa, Bronx, N. Y.

Application July 30, 1948, Serial No. 41,514

8 Claims. (Cl. 40—4)

1

This invention relates to new and useful improvements in display advertising devices, and, more particularly, the aim is to provide a novel and valuable such device for use on a dispensing container and so functioning that incidental to a dispensing of a product its designation or trade name will be then especially displayed in a manner strikingly to call attention to the same.

The new device is herein exemplifyingly embodied as applied to a dispensing bottle for a liquid, as a soft drink. As so embodied, the device comprises a casing carrying at one end a stopper or cork for the upper end of the bottle neck, an advertising sign on the casing, illuminating means for such sign inside the casing and incorporating an electric lamp bulb in a normally open circuit including a battery means as the current source, a liquid pour tube, an air inlet tube, and a mercury switch carried by the casing operable to close said circuit when and while the bottle is tilted for dispensing the liquid.

An object also is to provide a device as just broadly described, and one which is of relatively small size and weight, which may be produced at comparatively small cost, and which is readily disassemblable for replacing a battery element and/or the bulb.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view, showing a now favored embodiment of the invention, in place on a dispensing bottle indicated partially in dot and dash lines.

Fig. 2 is an enlarged top plan view of the device.

Fig. 3 is a vertical section, taken substantially on the line 3—3 of Fig. 2.

Fig. 4 is a horizontal section, taken on the line 4—4 of Fig. 3.

Fig. 5 is a top plan view of a plate carrying a socket for said bulb.

Fig. 6 is a top plan view of a disk-like insulating member carrying the contacts to coat with the mercury pool.

Fig. 7 is a top plan view of a plate downwardly centrally dished to provide a receptor for the pool of mercury.

Fig. 8 is a vertical section, taken on the line 8—8 of Fig. 7.

Fig. 9 is a horizontal section, taken on the line 9—9 of Fig. 3.

2

Referring to the drawings more in detail, the structure illustratively shown comprises a casing 15 of substantially elliptical cross-section having its side wall 16, its top wall 17, and a bottom flange 18 all parts of a single shell. The top wall 17 has a reduced upward extension 19, suitably apertured for the passage thereof of a liquid pour tube 20 and an air inlet tube 21.

The casing 15 lengthwise thereof, on one or both sides, carries a panel, such as that indicated at 22; such a panel for displaying the name of the drink, as "Kitty's," or any advertising matter in regard thereto. Preferably, the casing 15 is of thin sheet metal, and hence opaque; and a panel 22 is preferably of a suitably translucent material so carrying its advertising matter that ordinarily the latter may be read yet when the interior of the casing is illuminated the advertising matter will be suddenly and sharply visually accentuated. If the panel or panels 22 are not integral with the casing 15, as they could be were the casing made of a suitable plastic material, such a panel may be suitably set inside the casing opposite an opening therethrough, and held in place in any suitable way, as by a frame secured inside the casing for marginally engaging the panel beyond the bounds of its associated opening.

An electric lamp bulb is indicated at 23, and is shown as of the type having a screw base 24. The socket 25 for such base is formed integral with a thin spring metal plate 26, pierced as at 27 and 28 for the passage therethrough of the tubes 20 and 21 respectively. The plate 26 also has an opening 29, has struck up therefrom a spring tongue 30, and has three apertures 31 which are placed to match similar apertures through the bottom flange 18 of the casing 15, these apertures for taking small bolts 32 adapted to take small nuts 33, see Figs. 2 to 5.

For being positioned as shown in Fig. 3 below the plate 26 is the aforesaid disk-like insulating member 34 (see Fig. 6); this to be carried by a thin metal plate 35 (Figs. 7 and 8) centrally shaped to provide a cup-like receptor 36 for a pool 37 of mercury. The plate 35 beyond the cup 36, and outwardly toward a horizontal marginal flange 38 matching the flange 18 of the casing 15, is upwardly dished, to allow for interposition of the insulating member 34 between the plates 26 and 35, said flange 38 for matching the flange 18 of the casing 15 and having apertures 39 for matching the apertures 31 of the plate 26.

The insulating member 34 is circular in outline, and at a lower portion is of reduced diameter to provide a bottom annular shoulder 40 for force fit into the upper interior of the cup 36.

Said member 34 is an insulator, and of a shape to be readily inexpensively moulded of an insulating plastic material having positioned in situ therein the contacts for the mercury pool; one of such contacts being marked 41 and the other 42. The insulating member 34 has two cylindrical openings 43 and 44 therethrough, one to allow passage of the tube 20 and the other to allow passage of the tube 21. It will be noted from Fig. 6, that the contact 42 is extended, at its portion embedded in the member 34 so as to avoid contact with the tube 21, and that this contact beyond the member 34 is flattened and then curvilinearly bent on itself to provide a spring tongue 45 like the spring tongue 30, to which end the contact 42 is of spring metal.

The insulating member 34 is also shaped to have at its top a central downwardly tapering recess 46, across the bottom of which extends an intermediate length (see Fig. 3) of the contact 41.

The current source for the lamp 23 is here shown as comprising two dry-cell batteries 47, each held in the casing 15 at one of its two narrower ends by a leaf-spring type bracket 48 (Figs. 3 and 4) fixed on the casing side wall 16. Set in the upper end of the casing is an elliptical insulating ring 49 having secured thereto two like but reversely arranged contacts 50 and 51. These contacts are made of spring metal, as spring brass, and shaped so that when they are secured to the ring 49 as shown each contact has a bottom spring tongue 52 or 53 and a laterally offset and curvilinearly extending arm 54 or 55.

Thus, with said arms 54 and 55 conductively coupled by having soldered thereto as indicated the opposite ends of a short wire length 56, and with the two batteries 47 positioned as shown and described so that their end electrodes are resiliently engaged (the two electrodes of one battery between the spring tongues 30 and 52 and the two electrodes of the other battery between the spring tongues 45 and 53), a circuit is provided for energizing the bulb 23 which is wholly insulated from the casing and also from the plates 26 and 35 (the aforesaid opening 29 through the plate 26 being provided to avoid any chance of the tongue 45 of the contact 42 touching said plate); and in said circuit the two batteries are connected in series. Such circuit, however, is normally open, at the mercury switch including the contacts 41 and 42 and the pool 37, as shown in Fig. 3; that is, when the dispensing bottle 66 is resting on its bottom, upright. The plate 35, at the bottom of the cup 36, has apertures 57 and 58, respectively for having passed therethrough the tubes 20 and 21; these apertures surrounded by depending necks 59 and 60.

A third bottom plate 61 is provided, this also having a peripheral flange 62, for matching the flanges of the casing 15, of the plate 26 and of the plate 35; and said flange 62 is apertured to match the apertures 31 of the plate 26. Thus, when said casing and said three plates are assembled as in Fig. 3, they are locked together by the bolts 32 and nuts 33, thereby to establish the device as shown in Fig. 1. Yet the device may be quickly and easily opened up, merely by removing the three nuts, to get at the mercury switch, to substitute new batteries for the batteries 47, or to substitute a new bulb for the bulb 23.

Before the device is thus assembled, however, a cork or stopper 63 is forced down into the plate 61, for being gripped within a bottom skirt 64 of said plate; which latter has a very deeply dished

intermediate portion 65 intermediate the skirt 64 and the flange 62 of the plate. The cork or stopper 63 is provided with suitable channels therethrough for allowing passage of the tubes 20 and 21.

With the parts arranged as in Figs. 1 and 3, that is, with the bottle 66 normally standing upright, the circuit for the bulb 23 is broken at the contacts 41 and 42, as already stated. However, 10 immediately on lifting the bottle and substantially inverting it, thereby to dispense its liquid contents, the mercury pool 37 is displaced to bridge the contacts 41 and 42; and the panels 22 become brightly illuminated, by energization of the 15 bulb 23, by way of a circuit including the end terminal of the lamp base, the contact 41, the mercury pool 37, the contact 42, the battery 47 at the right in Fig. 3, the contact 51, the wire 56, the contact 50, the other battery, the spring tongue 30 of the plate 26, the plate 26 and the 20 socket 25 thereof engaging the other terminal of the bulb.

It is to be understood that instead of mercury, any other suitable liquid may be used to make 25 electrical contact.

While I have illustrated and described the preferred embodiment of my invention, it is to be understood that I do not limit myself to the precise construction herein disclosed and the right 30 is reserved to all changes and modifications coming within the scope of the invention as defined in the appended claims.

Having thus described my invention, what I 35 claim as new, and desire to secure by United States Letters Patent is:

1. An advertising device for a dispensing container of the kind to be displaced temporarily to an abnormal position incidental to a dispensing operation, comprising a casing, means carried by the casing for attaching the latter to said container, said casing carrying advertising matter, and electrical illuminating means for said advertising matter inside the casing and including a circuit interrupted by a gap and a means operable to close said gap when and only when the container is displaced to said abnormal position, the last-named means including a mercury switch, said container being one having a top opening for dispensing a liquid therethrough, the 45 first-named means being a stopper for closing said opening, and said device having a delivery means for said liquid including a liquid pour channel, said channel extending through said stopper, and also through the casing, said delivery means also incorporating an air inlet channel.

2. An advertising device for a dispensing container of the kind to be displaced temporarily to an abnormal position incidental to a dispensing 50 operation, comprising a casing, means carried by the casing for attaching the latter to said container, said casing carrying advertising matter, and electrical illuminating means for said advertising matter inside the casing and including a circuit interrupted by a gap and a means operable to close said gap when and only when the container is displaced to said abnormal position, the last-named means including a mercury switch, said container being one having 55 a top opening for dispensing a liquid therethrough, the first-named means being a stopper for closing said opening, and said device having a delivery means for said liquid including a liquid pour channel, said channel extending through said stopper, and also through the casing, said 60

70 a top opening for dispensing a liquid therethrough, the first-named means being a stopper for closing said opening, and said device having a delivery means for said liquid including a liquid pour channel, said channel extending through said stopper, and also through the casing, said 75

delivery means also incorporating an air inlet channel, each of said channels being a separate tube, each tube having a lower end below the bottom of the stopper and an upper end above the top of the casing.

3. An advertising device for a dispensing container of the kind to be displaced temporarily to an abnormal position incidental to a dispensing operation, comprising a casing, means carried by the casing for attaching the latter to said container, said casing carrying advertising matter, and electrical illuminating means for said advertising matter inside the casing and including a circuit interrupted by a gap and a means operable to close said gap when and only when the container is displaced to said abnormal position, the last-named means including a mercury switch, said container being one having a top opening for dispensing a liquid therethrough, the first-named means being a stopper for closing said opening, and said device having a delivery means for said liquid including a liquid pour channel, said channel extending through said stopper, and also through the casing, said delivery means also incorporating an air inlet channel, each of said channels being a separate tube, each tube having a lower end below the bottom of the stopper and an upper end above the top of the casing, there being in said casing a battery-type current source for said circuit.

4. An advertising device for a dispensing container of the kind to be displaced temporarily to an abnormal position incidental to a dispensing operation, comprising a casing, means carried by the casing for attaching the latter to said container, said casing carrying advertising matter, and electrical illuminating means for said advertising matter inside the casing and including a circuit interrupted by a gap and a means operable to close said gap when and only when the container is displaced to said abnormal position, the last-named means including a mercury switch, said container being one having a top opening for dispensing a liquid therethrough, the first-named means being a stopper for closing said opening, and said device having a delivery means for said liquid including a liquid pour channel, said channel extending through said stopper, and also through the casing, said delivery means also incorporating an air inlet channel, each of said channels being a separate tube, each tube having a lower end below the bottom of the stopper and an upper end above the top of the casing, there being in said casing a battery-type current source for said circuit, said source including a pair of batteries arranged one alongside the other, and each of said tubes being a straight tube, said tubes arranged between the two batteries.

5. An advertising device for a dispensing container of the kind to be displaced temporarily to an abnormal position incidental to a dispensing operation, comprising a casing, means carried by the casing for attaching the latter to said container, said casing carrying advertising matter, and electrical illuminating means for said advertising matter inside the casing and including a circuit interrupted by a gap and a means operable to close said gap when and only when the container is displaced to said abnormal position, the last-named means including a mercury switch, said container being one having a top opening for dispensing a liquid therethrough, the first-named means being a stopper for closing said opening, and said device having a delivery

means for said liquid including a liquid pour channel, said channel extending through said stopper, and also through the casing, said delivery means also incorporating an air inlet channel, each of said channels being a separate tube, each tube having a lower end below the bottom of the stopper and an upper end above the top of the casing, there being in said casing a battery-type current source for said circuit, said source 10 including a pair of batteries arranged one alongside the other, and each of said tubes being a straight tube, said tubes arranged between the two batteries, said illuminating means incorporating a lamp bulb positioned between said tubes.

15 6. An advertising device for a dispensing container of the kind to be displaced temporarily to an abnormal position incidental to a dispensing operation, comprising a casing, means carried by the casing for attaching the latter to said con-

20 the casing for containing the advertising matter, and electrical illuminating means for said advertising matter inside the casing and including a circuit interrupted by a gap and a means operable to close said gap when and only when the 25 container is displaced to said abnormal position, the last-named means including a mercury switch, said container being one having a top opening for dispensing a liquid therethrough, the first-named means being a stopper for closing

30 first-named means being a stopper for closing
said opening, and said device having a delivery
means for said liquid including a liquid pour
channel, said channel extending through said
stopper, and also through the casing, said de-
livery means also incorporating an air inlet chan-
nel, each of said channels being a separate tube,
35 each tube having a lower end below the bottom
of the stopper and an upper end above the top of
the casing, said tubes traversing the pooling
chamber for the mercury of said switch.

40 7. An advertising dispenser for use with a bottle containing a liquid to be dispensed and having a neck opening, comprising a hollow casing including a stopper at its bottom end for insertion into the neck opening of the bottle for mounting said casing on the top of the bottle, spaced air inlet and liquid dispensing tubes mounted substantially through the center of said casing and said stopper, a transparent advertising area formed in the side wall of said casing, an electric bulb mounted within said casing for illuminating said advertising area, an electric circuit for said bulb including a source of electric current within said casing and a pair of spaced contacts, and a pool of mercury within said casing, said spaced contacts being supported above said pool of mercury out of contact therewith, whereby when the bottle is inverted for dispensing some of the liquid through said liquid dispensing tube said pool of mercury will flow to contact said spaced contacts and complete said circuit to light said bulb and illuminate said advertising area.

8. An advertising dispenser for use with a bottle containing a liquid to be dispensed and having a neck opening, comprising a hollow casing including a stopper at its bottom end for insertion into the neck opening of the bottle for mounting said casing on the top of the bottle, spaced air inlet and liquid dispensing tubes mounted substantially through the center of said casing and 65 said stopper, a transparent advertising area formed in the side wall of said casing, an electric bulb mounted within said casing for illuminating 70 said advertising area, an electric circuit for said bulb including a source of electric current within 75 said casing and a pair of spaced contacts, and a

pool of mercury within said casing, said spaced contacts being supported above said pool of mercury out of contact therewith, whereby when the bottle is inverted for dispensing some of the liquid through said liquid dispensing tube said pool of mercury will flow to contact said spaced contacts and complete said circuit to light said bulb and illuminate said advertising area, a plate within said casing formed with an open topped cup containing said pool of mercury, and an insulation block closing the open top of said cup, said spaced contacts being mounted on said insulation block with the free ends depending into said cup but spaced from the top surface of said pool of mercury.
